TYPESETTING MEANS IN LAUNDRY
MARKING MACHINES

Joseph F. Anderson, Denver, Colo., assignor to
Burr Watson & Associates, Inc., Denver, Colo.,
a corporation of Colorado

Application April 23, 1947, Serial No. 743,263

3 Claims. (Cl. 101—95)

1

This invention relates to marking machines and more particularly to marking machines for printing identification marks on tags, clothing, articles of merchandise and the like.

One of the objects of my invention is to produce an improved marking machine which will be compact and small in size, simple and sturdy in construction, easy to operate and service, and economical to manufacture.

Another object is to embody in a marking machine having rotatable type wheels or equivalent members, an improved and compact means for rotating said type wheels or members to a desired printing position.

A further object is to produce an improved arrangement of gearing and a quadrant lever for rotating a type wheel or equivalent member to selected printing positions.

Yet another object is to provide improved means for properly and easily locating each of the numerous selective positions of each type wheel and yieldably maintaining the type wheel in the selected position.

A further object is to provide improved means for aligning the type wheels of a marking machine and locking said wheels against relative rotation.

A still further object is to produce improved mounting means for the type wheels of marking machines which will permit easy removal and assembly of the type wheels as a unit and thereby facilitate servicing or repair.

Other objects of the invention will become apparent from the following description taken in connection with the accompanying drawings showing, by way of example, a marking machine embodying said invention.

In the drawings:

Figure 1 is a perspective view of the marking machine;

Figure 2 is a vertical sectional view showing details of the structure for rotating the type wheels and yieldably maintaining such in any selected positions;

Figure 3 is a sectional view taken on the line 3—3 of Figure 2;

Figure 4 is a view showing the spring arrangement for liner bar;

Figure 5 is a side view showing the inker arm and platen arm assembly in the position assumed when inking is performed;

Figure 6 is another side view of part of the structure of Figure 5, but showing it in a position assumed when the platen arm is moved forwardly after inking has taken place; and

Figure 7 is a perspective view of a type wheel assembly showing another arrangement for the liner bar.

Referring to the drawings in detail and first to Figure 1, the marking machine disclosed has a

2

base member 1, side frame members 2 and 3 attached thereto and arranged in vertical spaced relation. The upper edges of these side frame members are curved, as shown, and attached thereto is an indicia or face plate 4 having slots 5 therein, through which extend the upper handle ends 6 of the quadrant or sector levers 7 shown in detail in Figure 2. The particular marking machine shown is provided with eight type wheels 10 for marking purposes and thus there are provided eight slots 5 in the indicia plate, one for each quadrant lever employed to selectively set a type wheel. Adjacent each slot are embossed or otherwise placed upon the indicia plate the indicia or characters to indicate the corresponding characters which are carried by the type wheels. The characters can be letters, numerals or any other symbols. In the marking machine shown there are both letters and numerals, the numerals 15 being adjacent the upper end portions of the slots and the letters extending from the numerals down to the lower ends of the slots. The marking machine can be provided with a suitable removable back plate so as to keep out foreign material, said plate not being disclosed in the perspective view of Figure 1.

Mounted between the two side frame members of the marking machine and adjacent the front opening thereof below the indicia plate is a type wheel assembly generally indicated by the numeral 8. In this type wheel assembly there are eight type wheels 9 positioned between two side plates or end members 10 and 11. Supported at its ends in suitable bosses in these side plates is 20 a sleeve type shaft 12 for rotatably mounting the type wheels. The ends of the sleeve shaft are suitably secured in the end plates so as to be removable when desired. Interposed between adjacent type wheels and also the side plates and 25 the end type wheels are thin spacer plates 13. As best shown in Figures 2 and 3, each spacer plate is provided with an extension 14 at the rear side thereof. A pin 15 extends through these extensions of the spacer plates and has its ends connected in similar extensions 16 of the side plates. Thus the side plates and spacer plates are held against relative rotation, but the type wheels are free to rotate on the sleeve shaft of the assembly. In order that the type wheel assembly may be properly mounted in the two side frames 2 and 3 of the marking machine, there is 30 provided a single headed rod 17 being arranged to be supported in suitable alignment openings in the two side frame members. This rod is held in the side members by means of a thumb screw 18 mounted in the forward edge of the frame side member 3.

In order that the side plates of the type wheel assembly, together with the spacer plates, may 35 be prevented from rotation on the rod 17, the

side plates 10 and 11 are provided with integral outwardly extending pins or lugs 19 and 20, as best shown in Figure 3. The lug 19 on the side plate 10 is arranged to be positioned between two spaced lugs or guides 21 and 22 extending inwardly from the side frame member 3. In a similar manner the lug 20 of the other side member of the type wheel assembly is arranged to extend between two lugs or guides 23 and 24 extending inwardly from the other side frame member 2. The lugs 19 and 20 on the side plates are positioned rearwardly of the axis of the type wheel assembly and therefore it will be seen that the side plates will be prevented from rotation, as will also the spacer plates 9 since they are connected to the side plates by the pin 15.

The particular type wheel assembly shown and the manner in which it is arranged to be mounted between the two side frame members 2 and 3 of the marking machine will permit the type wheel assembly to be readily removed from the machine as a unit so that this assembly can be cleaned, otherwise serviced or repaired. The removal of the assembly is accomplished by merely loosening the thumb screw 18, pulling the supporting rod 17 outwardly through the sleeve 12, and then sliding out the type wheel assembly by pulling forwardly thereon. The lugs 19 and 20 will thus be slipped from between the cooperating lugs on the inside of the side frame member. When it is desired to replace the type wheel assembly it can be grasped so that the lugs 19 and 20 are away from the hand and inserted between the side frame members so that these lugs slide in between their cooperating lugs on the side frame members. This will support the type wheel assembly while the sleeve 12 is axially aligned with the holes in the side frame members so that the rod 17 can be inserted in the sleeve 12 and the opening in the side frame member 3. The assembly will be completed when the thumb screw is turned up to hold the rod 17 in position.

The improved mechanism which is employed to rotate the type wheels of the marking machine to any selected positions is shown in detail in Figure 2 and reference thereto is now made. On a shaft 25 having its ends mounted in the side frame members 2 and 3 towards the back side of the marking machine are the previously referred to eight quadrant or sector levers 7 which are provided with the handle ends 6 positioned above the slots 5 in the indicia plate so as to be readily movable by the hand of the operator. Each quadrant or sector lever 7 has an arcuate portion 26 provided with teeth 27 on its inner curved edge. The arcuate portion is supported by a slightly curved connecting part 28 extending from the lever adjacent its pivot to the lower end of the arcuate portion. Forwardly of the shaft 25 forming the pivotal mounting for the quadrant levers is another shaft 29 having its ends supported in suitable bosses on the inside of the two side frame members 2 and 3 of the marking machine. On this shaft 25 are rotatably mounted eight spur gears 30, each of which is arranged to have its teeth 31 in meshing engagement with the teeth 32 of a type wheel, said teeth of the type wheel carrying on their outer ends the letters and numerals for accomplishing the printing or marking. Integral with each gear 30 is a smaller spur gear 33, the teeth 34 of which are arranged to mesh with the teeth 27 on the inner edge of the arcuate portion 26 of a quadrant lever. Thus with the integral gears 30 and 33 it is seen that by swinging a quadrant lever

7 about its pivot 25, there will be a transfer of rotary movement from the lever to a type wheel so that the type wheel can be rotated and set in any desired selected position. Since the spur gears 33 are considerably smaller than the gears 30, each quadrant lever can move in between the larger gears 30 as is well illustrated in Figure 2. The number of teeth on the spur gear 32 and the number of teeth on the gear 30 are so selected that any of the numbers or letters on a type wheel can be selected by moving the handle ends 6 of the quadrant levers from one end of its slot 5 to the other end of said slot.

In connection with the quadrant lever and gearing arrangement for operating each type wheel, it is to be particularly noted that by providing teeth on the inside edge of the arcuate portion 26 of the quadrant lever and employing the large and small gears 30 and 33 in association therewith and with the type wheels that it is possible in a very small space to obtain a complete 360 degree rotation of each type wheel by moving a quadrant lever through an arc which is only a small fraction of 360 degrees. The compact arrangement for rotating each type wheel results in a much smaller marking machine than could otherwise be obtained, particularly by such known type wheel actuating means wherein the type wheel is actuated directly by external teeth on a curved portion of a lever or by the inter-positioning of a gear between external teeth on a lever and the teeth of the type wheel. The particular actuating means disclosed between the quadrant lever and the type wheel has resulted in the production of a marking machine which is considerably less as to the height and depth of marking machines which are at present on the market and employing other types of driving means between a lever and a type wheel as all ready referred to.

In order that any selected position of the type wheel may be easily located and maintained against accidental shifting, there is provided a simple and efficient yielding means which is arranged to operate for each selected type wheel position. Pivotedly mounted on the same shaft 25 on which the quadrant levers are pivoted are eight arms 35. These arms are arranged alternately with the quadrant levers and such results in an arm lying in the same plane as the small gear 33 and extending beneath the said gear. These arms also act as spacer members between adjacent quadrant levers. On the upper edge of each of these arms is a curved portion 36 having such curvature as to be able to project partially in between adjacent teeth 31 of the large gear 30, but yet be easily pushed out from between said teeth and ride over a tooth whenever the quadrant lever and gear 30 is rotated. The rear end of each arm 35 has an extending portion 37 and to the free end of which there is connected one end of a coil spring 38. The other end of the spring is attached to a rod 39 extending between and supported in the two side frame members 2 and 3. It is thus seen that each spring 38 will so act on the arm 35 as to bias the arm upwardly so that its curved portion 36 can cooperate with the teeth 31 of the gear 30. Thus there is provided a position locating means for each movement of the gear 30 corresponding to the distance between teeth, and since the gear 30 meshes with teeth on a type wheel, then there will be a corresponding locating for each tooth of the type wheel which carries an indicia. It is to be particularly noted that the yieldable locating means for the

type wheels also functions by means of the arm 35 as a spacer between quadrant levers and thereby reduces the number of parts in the machine.

In order to rigidly lock the type wheels in any desired position and to also insure that the selected indicia or type on all the type wheels is properly aligned for marking purposes, there is provided a liner and locking bar 40, as shown in Figure 1, which is of a general U-shape, the leg portions of which are pivoted by pins 41 and 42 to the inside surfaces of the side frame members 2 and 3 at points slightly above the top of the type wheel assembly. The body portion of the liner bar thus can be swung to a position above the type wheel assembly so that it is free therefrom or can be swung downwardly so that the main body portion thereof will enter the spaces between teeth of the type wheels. If the spaces should be slightly out of alignment, the bar will bring them into alignment as it is pushed downwardly. The bar is provided with spaced flat members 43 and 44 at its forward side so as to provide finger grasping means to permit easy swinging of the liner bar. The forward edges of the side frame members are formed with short inwardly extending flanges 45 and 46 and it is to be noted that the legs of the aligning bar are bent to fit around these flanges. On the inside of one of the flanges, as 45, there is attached a leaf spring 47 (shown in detail in Figure 4) and this leaf spring is so formed and so cooperates with a bent part of the bar as to provide a yieldable means for holding the bar in any desired position. Thus if the bar is swung upwardly away from the type wheel the spring will insure that the bar will be held free of the wheel and not drop down and interfere with the rotation of the type wheels.

In place of mounting the liner bar on the two side frame members, the bar can be mounted on the type wheel assembly. Such an arrangement is shown in Figure 7. In this arrangement the liner bar 48 is provided with an L-shaped extension 49 which is pivoted to the side plate 10, for example, of the type wheel assembly. A finger grasping member 50 is provided near the juncture of the liner bar and extension 49 so as to facilitate swinging the bar either to a locking position with the type wheels or free of the type wheels. In order that the bar may be held in its various positions, there is provided a coil spring 49' connected at one end to the elbow of the L-shaped extension 49 and at the other end to the side plate 10. When the liner bar is swung away from the type wheels this spring will be moved so as to be slightly over center with respect to the pivotal axis of the L-shaped arm 49 and it can thus hold the liner bar in its inoperative position. When the liner bar is moved into engagement with the type wheels to perform its aligning and locking operations, the spring will be so positioned that it will be effective to hold the liner bar in operative position.

Referring now to Figures 1, 5 and 6, the lower front corners of the two side frame members have mounted therein the ends of a shaft 51 upon which is pivoted the inker and platen assembly generally indicated by the numeral 52. This assembly has a hub portion 53 pivoted on the shaft 51 and integral therewith and extending therefrom in diverging relationship is the platen or printer arm 54 and the inker arm 55. The upper end of the platen arm carries a handle 56 having rounded hand grasping portions at its ends. Mounted on the central part of this handle is

a platen clip 57 and the platen 58. The inker arm 55, at its upper end, has pivotally mounted thereon an inker assembly generally indicated by the numeral 59 and comprising an inker member 60 pivoted to the inker arm 55 by a pin 61. The inker member carries the inker pad 62 between opposite side flanges 63 and 64, which flanges carry rollers 65 and 66 adapted for engagement with the side plates 10 and 11 of the type wheel assembly (see Figure 5) and to roll thereon, as will be later described. These side plates 10 and 11 are also provided with curved recesses 67 and 68 for receiving the rollers 65 and 66, respectively, so that as the inker arm is moved forwardly the inker pad can engage the presented type and apply ink thereto. The inker member 60 has attached thereto a spring 69 which extends downwardly along the forward side of inker arm 55 and has its lower end attached to the lower portion of the inker arm. This spring normally maintains the inker member in aligned relationship with the inker arm 55 which is determined by stops 70. The inker member, however, is permitted to swing backwardly with respect to the inker arm 55 under yielding of the spring. This swinging rearwardly will occur when the inker arm is moved forwardly to cause the inker pad to engage the type of the type wheels. The rearward swinging will continue as the inker arm is continued to be moved forwardly by the moving of the handle and the platen arm forwardly towards the type wheel assembly. As the inker arm 55 moves forwardly beneath the type wheel assembly, the rollers will move out of the recesses 67 and 68 and on to the circular edges of the side plates of the type wheel assembly as illustrated in Figure 6. This will result in the inker pad being moved outwardly away from the type wheels, remaining away from it as the rollers roll down the edges of the side plates of the type wheel assembly. Thus the inker assembly will be moved out of the path of movement of the platen 58 as the platen arm moves forwardly. Printing will occur when the platen arm engages any tag or other material placed over the face of the platen and this tag or other material is forced by the movement of the platen arm into engagement with the type wheels. It is to be particularly noted that the construction of the inker arm, inker assembly and platen arm is very simple and because of the integral arrangement of the hub, the inker arm 55 and the platen arm, one pivot can be employed for the whole mechanism, thus decreasing the number of parts.

In order to provide a yieldable retractile stop for the inker arm and platen arm, the base 1 of the machine carries the rubber bumper 71 and when the platen arm engages this bumper the inker assembly will be in inoperative position where said assembly is spaced away from the type wheels as shown in Figure 1.

From the foregoing description of the illustrated marking machine embodying my invention, it is seen that it is very compact as to size and that a minimum number of parts are employed in its construction, thus resulting in a low cost of manufacture. The marking machine is very easily operated, as all that needs be done is select the desired characters by operating the quadrant levers to positions indicated on the indicia plate alongside of each slot. This will then locate each type wheel so that the indicia thereon which is presented for engagement by the platen 58 will correspond to the indicia on

the indicia plate as selected by a quadrant lever. If it is desired to lock the type wheels in their selected positions, the liner bar employed can be lowered, which will also insure that the selected characters or type on the type wheels will be in proper alignment. To accomplish the printing, the article to be printed is placed over the platen, the handle 56 grasped and the platen arm swung forwardly. If a tag is to be marked, a suitable tag holder might be employed to hold the tag on the face of the platen. If a piece of cloth or paper is to be printed it can be conveniently held by the hands as they are employed to grasp the ends of the handle. The initial forward movement of the handle and platen arm will bring the inker pad into engagement with the selected type, thus placing ink on the type, which occurs just prior to the rollers entering the recesses 67 and 68 as illustrated in Figure 5. During inking the inker assembly will be moved backward somewhat with respect to the inker arm. Continued forward movement of the handle and platen arm will then result in the further bending backward of the inker assembly relative to the inker arm as the rollers move out of the recesses 67 and 68 in the side plates 10 and 11 of the type wheel assembly, all as illustrated in Figure 6. The upper end of the inker arm 55 will thus continue to move under the type wheel assembly and the inker assembly will follow it with the inker pad out of contact with the type of the type wheel. When the platen arm is moved so that the tag or other material is forced into engagement with the type by the platen 58, printing will occur. The handle and platen arm are then returned to their initial position, as shown in Figure 1, which will result in the inker assembly on the end of the inker arm 55 also assuming the position shown in Figure 1.

In the particular marking machine shown, full 380 degree type wheels are employed, but in place thereof quadrants can be employed with type thereon if desired, particularly where fewer characters are to be printed. It is, therefore, to be understood that the word type wheel is intended to include any rotatable member having type thereon. The number of type wheels and rotatable gears and quadrant levers can be varied as desired. Therefore, being aware of the possibility of modifications of the particular structure shown and described without departing from the fundamental principles of my invention, it is not intended that the scope of said invention be limited in any manner except in accordance with the appended claims.

What is claimed is:

1. In a marking machine having a plurality of rotatable members each provided with printing type on the peripheral portion and all being rotatable on a common axis, a plurality of pivoted levers mounted on a common shaft, gearing means between each lever and a type carrying rotatable member for rotating the latter to selected positions, and means cooperating with teeth of the gearing means between each lever and a rotatable member for yieldably holding a rotatable member in any selected position, each of said last named means comprising an arm pivoted on the pivot shaft of the levers and having a portion for partial reception in the space between gearing teeth to permit rotation of the gearing means in either direction, and spring means acting on the arm and yieldably opposing the movement of the arm portion from said partial reception posi-

tion, said arms being alternately arranged with the levers.

2. In a marking machine having a plurality of rotatable members each provided with printing type on the peripheral portion and all being rotatable on a common axis, a plurality of pivoted levers mounted on a common shaft, each of said levers having an arcuate portion with the axis of the lever as its center and being provided with inwardly extending teeth, a plurality of sets of gears rotatable on a common axis, each set comprising two gears of different size connected to rotate together with the teeth of the smaller gear of each set meshing with the teeth on a lever and the larger gear of said set arranged to rotate in a plane adjacent to the plane of movement of the lever, means for rotating a type carrying rotatable member by the larger gear of each set, and means for cooperating with the teeth of the larger gear of each set for yieldably holding the gear in positions it assumes when rotated through a space between teeth or any multiple thereof, each of said last named means comprising an arm pivoted intermediate its ends on the pivot shaft of the levers and lying in the plane of rotation of a larger gear, one end of said arm being provided with a portion for partial reception between teeth of a larger gear, and a spring acting on the other end of the arm for biasing the said one end of the arm for cooperation with the teeth of the larger gear, said arms being alternately arranged with respect to the levers and the arms between adjacent levers acting as spacer members.

3. In a marking machine having a plurality of rotatable members each provided with printing type on the peripheral portion and all being rotatable on a common shaft, a plurality of levers mounted on a common pivotal shaft positioned rearwardly of the members, gearing means between each lever and a type carrying rotatable member for rotating the latter to selected positions, and a means cooperating with teeth of each gearing means between each lever and a rotatable member for yieldably holding a rotatable member in any selected position, said last named means including a yieldably operated member pivoted on the pivotal shaft of the levers, said yieldably operated members being alternately arranged with the levers and capable of permitting rotation of the gears in either direction while engaging the teeth thereof.
